PAGE 2

Figure 1 is a perspective view of an automobile embodying my new design. The portions of the automobile not shown are conventional;

Figure 2 is an enlarged view of the center headlamp arrangement shown in full lines in Figure 1;

Figure 3 is a top plan view of the arrangement shown in Figure 2;

Figure 4 is an enlarged side elevational view of the arrangement shown in Figure 2, and

Figure 5 is a sectional view taken along the line generally indicated by line 5-5 of Figure 2.

The dominant features of my design reside in the full line portions of the drawings.

I claim:
The ornamental design for an automobile, substantially as shown and described.
